[57] CLAIM

The ornamental design for a wrist watch with nautical design, as shown and described.

DESCRIPTION

FIG. 1 is a front perspective view of a 6-spoked wrist watch with nautical design showing my new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof; and,

FIG. 7 is a front perspective view of another embodiment of my new design of FIGS. 1-6, the sole difference being the provision of eight spokes.
